UNITED STATES PATENT OFFICE.

WALTER LARKIN, OF NORRISTOWN, PENNSYLVANIA, ASSIGNOR TO FIDELITY MACHINE COMPANY, OF WILMINGTON, DELAWARE, A CORPORATION OF DELAWARE.

VERTICAL STRIPE FOR WIDE-CIRCULAR-RIB-KNITTING MACHINES.

Application filed May 28, 1927. Serial No. 194,956.

This invention relates especially to wide, circular rib knitting machines which are adapted to knit tubular undershirting and similar fabrics.

5 The principal object of the invention is to provide mechanism which can be applied to existing machines for the purpose of producing longitudinal stripes on the face of the fabric being knitted.

10 The construction of my invention will be fully disclosed hereinafter, reference being had to the accompanying drawings of which:

Fig. 1 is a sectional elevation of sufficient of a wide circular rib knitting machine to 15 illustrate my invention as applied thereto;

Fig. 2 is a sectional plan view taken on the line 2—2 of Fig. 1;

Fig. 3 is an enlarged side elevation of a portion of the mechanism shown in Figs. 20 1 and 2;

Fig. 4 is a plan view of the mechanism shown in Fig. 3, with the top plate or bobbin carrier removed;

Fig. 5 is a sectional elevation of a detail of 25 the invention, and

Fig. 6 illustrates a modification of the invention.

Referring to Fig. 1, the main base plate of 30 a wide circular rib knitting machine is indicated at 1. In the present instance, a vertical and stationary needle cylinder 2 is secured to the base plate 1 by any suitable means (not shown). The cylinder 2 is provided with the usual vertical grooves 3 in 35 each of which is operatively mounted a cylinder needle 4.

The base plate 1 is provided with a circular cavity 5, in which is rotatably mounted a rotatable cylinder cam plate 6. The cam plate 6 carries the cylinder needle cam ring 7 in which is secured the usual needle operating cams 8, which cooperate with the butts 9 of the cylinder needles 4. Adjacent the periphery of the cylinder cam plate 6, the said plate is provided with a ring gear 10 through which the said cylinder cam plate 6 and cam ring 7 are rotated by means (not shown) forming no part of the present invention.

50 Columns 11 are secured to and extend vertically from the cylinder cam plate 6, and at their upper ends support a spider having arms 12 which are suitably secured to the columns 11. The central hub 13 of the spider

supports a dial post 14. A needle dial 15 is 55 loosely mounted on the lower end of the dial post 14, being supported thereon by a bearing plate 16 which is secured to the dial post 14 by means of a nut 17 applied to a reduced threaded portion 18 of said post. 60

The needle dial 15 is provided with the usual series of radially disposed grooves 19 in each of which is suitably secured a needle separator 20. These needle separators 65 cooperatively form grooves 21 in which are slidably mounted the individual dial needles 22. The individual dial needles 22 are adapted to be projected between each adjacent pair of cylinder needles 4, in the usual manner, by means of dial cams 23 which are 70 secured on the under side of a dial cap 24.

The dial cap 24 is suitably mounted on the dial post 14 and is rotated therewith by means of a key rod 25, one end of which is mounted in a bearing 26 secured to the 75 upper side of the dial cap 24, the opposite end being secured in a lug 27 on one of the spider arms 12.

The dial post 14 is slidable vertically in the hub 13 of the dial supporting spider for 80 the adjustment of the needle dial 15 relative to the needle cylinder 2. The adjustment of the dial 15 relative to the cylinder 2 is accomplished through the dial post 14 by a threaded nut 28 cooperating with a reduced 85 threaded portion 29 on the upper end of the dial post 14, the nut 28 bearing on a washer 30 which in turn rests on the upper end of the spider hub 13. The dial post 14 is prevented from turning in the spider hub 13 90 by any suitable means, such, for example, as that illustrated in Fig. 1, which consists of a pin 31 extending through the spider hub 13 and through a slot 32 formed in the post 14. 95

The cylinder cam plate 6, the cam ring 7, columns 11, spider 12—13, dial post 14, and dial cap 24 rotate as a unit while the needle cylinder 2 and needle dial 15 remain stationary. The needle cylinder 2, as above mentioned is secured to the base plate 1 and the needle dial 15 is prevented from turning by the usual dogs (not shown) which 100 cooperate with the said needle dial 15 and the said needle cylinder 2, to prevent relative rotation between these elements.

The above described elements are common 105 in the type of machine above referred to and

form no part of my present invention which consists of providing striping or plaiting fingers in vertical alignment with any desired number of the cylinder needles, and operating these plaiting fingers in such a manner as will cause each of the individual fingers to wrap a separate plaiting thread around the cylinder needle with which that particular finger is in alignment.

1⁶ In the present instance, I provide a striping finger carrier 50 in the form of a cylinder held rigidly in coaxial alignment with and positioned above the needle cylinder 2. The cylindrical carrier 50 is provided with 15 a thickened portion 51, adjacent its upper end, in which is formed a plurality of groups of vertically disposed grooves 52. In any desired number of the grooves 52 of each group, I mount striping or plaiting 20 fingers 53. The plaiting fingers of each group are loosely mounted on a pivot wire 54 which lies in a circumferential groove 55 formed in the thickened portion 51 of the carrier 50. The pivot wire 54 is composed 25 of a plurality of sections, one for each group of plaiting fingers 53 and is secured, at each of its ends, within the groove 55, by means of screws 56—56, the heads of which overlap the said wire and hold it in place. The 30 screws 56 are located in non-grooved portions of the carrier 50 between the adjacent groups of finger grooves 52 formed therein.

The thickened portion 51 of the carrier 50 is provided with a second or internal 35 horizontally disposed groove 57 directly behind the pivot rod groove 55. The groove 57 extends outward from the inner wall of the carrier to a point beyond the base of the finger grooves 52, thus the grooves 52 40 communicate with the interior of the cylindrical carrier 50 throughout a portion of their length, directly behind and substantially an equal distance above and below the pivot wire 54.

45 Each of the plaiting fingers 53 is provided with a rear portion which extends into the internal groove 57 of the carrier 50, and is provided with a substantially straight edge 58 adapted to be engaged by operating 50 cams 59 and 60. Each finger 53 extends downwardly from the pivot wire 54 and is provided with a needle engaging foot portion 61 which is bent at an angle with respect to the general plane of the finger, (see 55 Fig. 3). Each finger 53 is further provided with thread eyes 62, through which individual plaiting threads pass from bobbins 63 carried by the finger carrier 50.

The bobbins 63 are supported on a bobbin 60 carrier ring 64 which is composed of a series of segments 65—65. Each segment comprises a lower step 66 and an upper step 67. The steps 66 and 67 are integrally connected by upright members 68. The periphery of 65 the upper step 67 is provided with a series

of outwardly extending lugs 69 to which are secured the opposite ends of thread guide plates 70, by means of screws 71.

The upper step 67 of each bobbin carrier segment 65 overlies the upper edge of the 70 finger carrier cylinder 50 and is secured thereto by means of screws 72, passing through apertures formed in said steps and entering threaded apertures in the upper edge of said finger carrier cylinder 50. 75

The finger carrier cylinder 50 is rigidly supported on the needle dial 15 in the following manner: In vertical alignment with the non-grooved portions 73 of the finger carrier cylinder 50 the ordinary dial needle 80 separators 20 are replaced by special separators 75, each of which is provided with a vertically extending neck 76 which fits within a shoulder recess 77 formed in the lower peripheral edge of the carrier 50. The necks 85 76 of the needle separators 75 each have an outwardly projecting lug 78 at their upper end under the lower edge of which a lug 79 on a clamp plate 80 projects. The clamp plates 80 are each secured to the carrier 50 90 by means of a screw 81.

The operating cams 59 and 60 are each mounted on the upper end of a post 82 and 83 respectively. The cam posts are rigidly secured in the upper side of the dial cap 24 95 and are carried around the dial post 14 with and by the said dial cap 24.

It will be understood that in machines of this general type a plurality of body thread guides are provided, which are spaced 100 equally around the machine, being carried by the cylinder cam ring 7. For each thread guide there is a corresponding series of cylinder needle operating cams on the said cylinder cam ring 7 and a like series of dial 105 needle operating cams on the dial cap 24. I also provide a pair of finger operating cams 59 and 60 for each body thread guide, in order that the plaiting fingers will be operated for each course of body stitches formed by 110 the machine.

In operation, as the cylinder cam ring 7 and the dial cap 24 are rotated the cylinder and dial needles are manipulated in the usual manner to form successive courses of stitches comprising the body of the fabric being produced. While the cylinder needles 4 are in their raised position the finger operating cam 60 successively engages the rear edges 115 58 of the plaiting fingers 53, below the pivot 54 thereof, and forces the fingers outwardly. The outermost face of the angularly disposed foot portion 61 of each finger engages the rear edge of the cylinder needle with which the finger is aligned and causes the foot of 120 the finger to move off to one side of the said needle, thence, due to the resiliency of the material of which the finger is composed, the finger again assumes a position in vertical alignment with, but in front of, the said 125

needle. The finger has thus carried the plaiting thread to and around one side of the needle. The cam 60 now moves out of engagement with the finger 53 and the finger operating cam 59 is moved into engagement with the rear edge 58 of the finger above the pivot 54 thereof, thereby turning the finger on its pivot and returning it to its normal inner position. In traveling from its outer 16 to its inner position the rear face of the angularly disposed foot portion 61 of the finger engages the front edge of the needle and causes the finger to move off to the opposite side of the needle, thus carrying the plaiting 21 thread completely around the needle as it returns to its innermost position.

The fingers 53 are each given a slight twist in their upper portions which lie within the respective grooves 52, in order that the 26 fingers will bind slightly in their grooves and thus be maintained in any position to which they may be moved by their operating cams 59 and 60.

If desired, I may form a notch 90 (Fig. 6) 23 in each of the fingers 53^a, below the pivot 54^a thereof, and place a spring band 91 in the said notches which will extend completely around the finger carrier cylinder 50^a and tend to return the fingers to, and 30 maintain them in, their inner or inoperative position, thus preventing the fingers from being accidentally moved to their outer or thread laying positions.

In Fig. 6, I have also illustrated a modified form of means for securing the finger carrier cylinder 50^a to the dial 15^a. In this form of the invention, a circular depending flange 92, formed by the production of the shoulder recess 77^a is pressed into notches 40 93, one of each of which is formed in the rear side of each of the necks 76^a of needle separators 75^a. In this instance, the needle separators 75^a are formed integral with the dial 15, and are produced by the cutting of the 45 needle grooves 21^a. With this means of fastening the finger carrier in place, the carrier may be provided with a finger groove in alignment with each cylinder needle if desired, in place of these grooves being divided into groups. The pivot wire 54^a in such case would be a continuous spring ring, which will be self-sustaining in its retaining 50 groove 35^a.

The bobbins 63 are each enclosed by a glass 65 cover 94, which is centered around the bobbin supporting pin 95 by means of a flanged bottom plate 96. Each cover 94 is provided with an opening 97 in its apex through which the plaiting thread *x* extends from the bobbin 63 in the cover to one of the thread eyes 98 in the thread guide plates 70, and thence to and through the thread eyes 62 formed in the plaiting fingers 53.

I claim:

65 1. In combination with a wide circular rib

knitting machine having a needle cylinder and needles operatively mounted therein, a needle dial and needles operatively mounted therein, a cylinder cam ring for operating the cylinder needles, and a dial cap having 70 cams for operating the dial needles; a cylindrical plaiting finger carrier coaxially aligned with said needle cylinder; means for rigidly securing said carrier to said needle dial; plaiting fingers pivotally mounted in 75 said carrier and aligned with certain of said cylinder needles, and means for moving one end of each finger around the needle with which it is aligned, for carrying a plaiting thread around said needle. 80

2. In combination with a wide circular rib knitting machine having a needle cylinder and needles operatively mounted therein, a needle dial and needles operatively mounted therein, a cylinder cam ring for operating 85 the cylinder needles, and a dial cap having cams for operating the dial needles; a cylindrical plaiting finger carrier coaxially aligned with said needle cylinder and rigidly secured to said needle dial; vertical 90 grooves formed in the periphery of said carrier; plaiting fingers pivotally mounted in said vertical grooves and aligned with certain of said cylinder needles; and means for moving one end of each finger around the 95 needle with which it is aligned, for carrying a plaiting thread around said needle.

3. In combination with a wide circular rib knitting machine having a needle cylinder and needles operatively mounted therein, a needle dial and needles operatively mounted therein, a cylinder cam ring for operating the cylinder needles, and a dial cap having 100 cams for operating the dial needles; a cylindrical plaiting finger carrier coaxially aligned with said needle cylinder and rigidly secured to said needle dial; vertical grooves 105 formed in the periphery of said carrier; plaiting fingers pivotally mounted in said vertical grooves and aligned with certain of said cylinder needles; a circumferential groove formed in the periphery of said carrier; a pivot wire in said circumferential groove on which said fingers are mounted; and means for moving one end of each finger 110 around the needle with which it is aligned, for carrying a plaiting thread around said needle. 115

4. In combination with a wide circular rib knitting machine having a needle cylinder and needles operatively mounted therein, a needle dial and needles operatively mounted therein, a cylinder cam ring for operating the cylinder needles, and a dial cap having 120 cams for operating the dial needles; a cylindrical plaiting finger carrier coaxially aligned with said needle cylinder and rigidly secured to said needle dial, vertical grooves 125 formed in the periphery of said carrier and arranged in separated groups therearound; 130

22
plaighting fingers pivotally mounted in said vertical grooves and aligned with certain of said cylinder needles; a circumferential groove formed in the periphery of said carrier; a pivot wire in said circumferential groove on which said fingers are mounted; means located intermediate said groups for removably securing said pivot wire in place; and means for moving one end of each finger 10 around the needle with which it is aligned, for carrying a plaighting thread around said needle.

5. In combination with a wide circular rib knitting machine having a needle cylinder 15 and needles operatively mounted therein, a needle dial and needles operatively mounted therein, a cylinder cam ring for operating the cylinder needles, and a dial cap having cams for operating the dial needles; a cylindrical plaighting finger carrier coaxially aligned with said needle cylinder; plaighting fingers pivotally mounted in said carrier and aligned with certain of said cylinder needles; needle separators in said dial having 20 necks engaging said carrier; means for securing said carrier to said needle separator necks; plaighting fingers pivotally mounted in said carrier and aligned with certain of said cylinder needles; and means for moving one 25 end of each finger around the needle with which it is aligned, for carrying a plaighting thread around said needle.

6. In combination with a wide circular rib knitting machine having a needle cylinder 30 and needles operatively mounted therein, a needle dial and needles operatively mounted therein, a cylinder cam ring for operating the cylinder needles, and a dial cap having cams for operating the dial needles; a cylindrical plaighting finger carrier coaxially aligned with said needle cylinder; vertical 35 grooves formed in the periphery of said carrier and arranged in separated groups therearound; plaighting fingers pivotally mounted in said vertical grooves and aligned with certain of said cylinder needles; needle separators in said dial having necks engaging 40 said carrier; means located intermediate said groups for securing said needle divider necks to said carrier; and means for moving one end of each finger around the needle with which it is aligned, for carrying a plaighting 45 thread around said needle.

7. In combination with a wide circular rib 50 knitting machine having a needle cylinder and needles operatively mounted therein, a needle dial and needles operatively mounted therein, a cylinder cam ring for operating the cylinder needles, and a dial cap having 55 cams for operating the dial needles; a cylindrical plaighting finger carrier coaxially aligned with said needle cylinder; vertical grooves formed in the periphery of said carrier and arranged in separated groups there- 60 around; plaighting fingers pivotally mounted 65

in said vertical grooves and aligned with certain of said cylinder needles; a shouldered recess formed in the lower peripheral edge of said carrier; needle separators in said dial having shouldered necks within 70 said recess; shouldered clamp plates located intermediate said groups and engaging said shouldered separator necks for securing said carrier to said needle dial; and means for moving one end of each finger around the 75 needle with which it is aligned, for carrying a plaighting thread around said needle.

8. In combination with a wide circular rib knitting machine having a needle cylinder 80 and needles operatively mounted therein, a needle dial and needles operatively mounted therein, a cylinder cam ring for operating the cylinder needles, and a dial cap having cams for operating the dial needles; a cylindrical plaighting finger carrier coaxially 85 aligned with said needle cylinder and rigidly secured to said needle dial; plaighting fingers pivotally mounted in said carrier and aligned with certain of said cylinder needles; cams secured to said dial cap and adapted to engage said fingers, for moving one end of each finger around the needle with which it is aligned, for carrying a 90 plaighting thread around said needle.

9. In combination with a wide circular rib 95 knitting machine having a needle cylinder and needles operatively mounted therein, a needle dial and needles operatively mounted therein, a cylinder cam ring for operating the cylinder needles, and a dial cap having 100 cams for operating the dial needles; a cylindrical plaighting finger carrier coaxially aligned with said needle cylinder and rigidly secured to said needle dial; plaighting fingers pivotally mounted in said carrier 105 and aligned with certain of said cylinder needles; cams secured to said dial cap and adapted to engage said fingers successively at opposite sides of their respective pivots for moving one end of each finger around 110 the needle with which it is aligned, for carrying a plaighting thread around said needle.

10. In combination with a wide circular rib knitting machine having a needle cylinder 115 and needles operatively mounted therein, a needle dial and needles operatively mounted therein, a cylinder cam ring for operating the cylinder needles, and a dial cap having cams for operating the dial needles; a cylindrical plaighting finger carrier 120 coaxially aligned with said needle cylinder and rigidly secured to said needle dial; vertical grooves formed in the periphery of said carrier; a horizontal groove formed in the interior face of said carrier and extending through the wall thereof to the base of 125 said vertical grooves; plaighting fingers pivotally mounted in said vertical grooves and aligned with certain of said cylinder needles; cams secured to said dial cap and op- 130

- erable in said interior horizontal groove and adapted to engage said fingers successively at opposite sides of their respective pivots, for moving one end of each finger around 5 the needle with which it is aligned, for carrying a plaiting thread around said needle.
11. In combination with a wide circular rib knitting machine having a needle cylinder and needles operatively mounted therein, a needle dial and needles operatively mounted therein, a cylinder cam ring for 10 operating the cylinder needles, and a dial cap having cams for operating the dial needles, a cylindrical plaiting finger carrier coaxially aligned with said needle cylinder and rigidly secured to said needle dial; plaiting 15 fingers pivotally mounted in said carrier and aligned with certain of said cylinder needles; means on said carrier for supporting striping thread bobbins; means for guiding said striping threads to said fingers; and 20 means for moving one end of each finger around the needle with which it is aligned, for carrying a plaiting thread around said needle.
12. In combination with a wide circular rib knitting machine having a needle cylinder and needles operatively mounted therein, a needle dial and needles operatively mounted therein, a cylinder cam ring for 25 operating the cylinder needles, and a dial cap having cams for operating the dial needles; a cylindrical plaiting finger carrier coaxially aligned with said needle cylinder and rigidly secured to said needle dial; vertical 30 grooves formed in the periphery of said carrier; a circumferential groove formed in the peripheral face of said carrier at right angles to said vertical grooves; a horizontal groove formed in the interior face of said carrier and extending through the wall thereof to the base of said vertical grooves; plaiting fingers pivotally mounted 35 in said vertical grooves and aligned with certain of said cylinder needles; a pivot wire in said circumferential groove on which said fingers are mounted; cams secured to said dial cap and operable in said interior horizontal groove and adapted to engage said fingers successively at opposite sides of their respective pivots, for moving one end of each finger around the needle with which it is aligned, for carrying a plaiting thread 40 around said needle.
13. In combination with a wide circular rib knitting machine having a needle cylinder and needles operatively mounted therein, a needle dial and needles operatively mounted therein, a cylinder cam ring for 45 operating the cylinder needles, and a dial cap having cams for operating the dial needles; a cylindrical plaiting finger carrier coaxially aligned with said needle cylinder and rigidly secured to said needle dial; plaiting 50 fingers pivotally mounted in said carrier and aligned with certain of said cylinder needles; means on said carrier for supporting striping thread bobbins; means for guiding said striping threads to said fingers; and 55 means for moving one end of each finger around the needle with which it is aligned, for carrying a plaiting thread around said needle.
14. In combination with a wide circular rib knitting machine having a needle cylinder and needles operatively mounted therein, a needle dial and needles operatively mounted therein, a cylinder cam ring for 60 operating the cylinder needles, and a dial cap having cams for operating the dial needles; a cylindrical plaiting finger carrier coaxially aligned with said needle cylinder and rigidly secured to said needle dial; plaiting 65 fingers pivotally mounted in said carrier and aligned with certain of said cylinder needles; a bobbin supporting ring secured to said finger carrier; thread eyes on said bobbin ring for guiding striping threads from the bobbins to the fingers; and 70 means for moving one end of each finger around the needle with which it is aligned, for carrying a plaiting thread around said needle.

WALTER LARKIN.
